UNITED STATES PATENT OFFICE.

SYDNEY B. AUSTIN, OF PIKESVILLE, MARYLAND, ASSIGNEE, BY MESNE ASSIGNMENTS, TO AUSTIN ADDING MACHINE CORPORATION, OF DELAWARE.

ADDING, SUBTRACTING, AND MULTIPLYING MACHINE.

1,034,865.

Specification of Letters Patent.

Patented Aug. 6, 1912.

Application filed March 31, 1910, Serial No. 552,736. Renewed December 4, 1911. Serial No. 663,827.

To all whom it may concern:

Be it known that I, SYDNEY B. AUSTIN, citizen of the United States, residing at Pikesville, Baltimore county, Maryland, have invented certain new and useful Improvements in Adding, Subtracting, and Multiplying Machines, of which the following is a specification.

My invention relates to adding, subtracting and multiplying machines, and in carrying out my invention I provide a selector device pivotally mounted and consisting of a single element which is toothed, and into which transmitting wheels or members are shifted when the selector is turned to different angular positions according to the values of the keys struck, so that when these transmitting wheels have all been set back according to the values of the operated keys, 20 a movement of the selector device about its axis by means of the operation of a handle or other suitable operating member will cause the rotation of the transmitting wheels or members, and the engagement of said members with the totalizer wheels, so that the values of the keys operated will be set up on the totalizer, after which the transmitting wheels will be shifted automatically in an axial direction and laterally in respect to the totalizer wheels to assume positions out of engagement therewith, and in line with the spaces between them, while, however, still maintaining their connection with the selector device to be set back thereby, after which the transmitting wheels, as a group, will be shifted to their disengaged position.

The invention embodies certain features whereby the group of mechanism above mentioned may be operated for subtracting or multiplying.

The invention consists in the features and combination and arrangement of parts hereinafter described and particularly set forth in the claims.

In the accompanying drawings Figure 1 is a plan view of so much of an adding machine as is necessary for a clear understanding of my invention; Fig. 2 is a view looking from the front of Fig. 1; Fig. 3 is a sectional view from front to rear substantially on the line 3-3 of Fig. 1; Fig. 4 is a sectional view from front to rear substantially on the line 4-4 of Fig. 1; Figs. 5 and 6 are views of details.

In these drawings, 1 indicates the keys of the adding machine numbered from 1 to 9, and in addition the set includes a cipher key. These keys are carried by levers 2 pivotally mounted on a shaft 3 suitably supported in the frame, the movement of the levers being communicated to the shaft through pins 4 and 5 which are set relatively to each other in respect to the different keys to transmit different degrees of rotary motion to the said shaft 3 according to the value of the key struck, the said key levers being loosely mounted on the said shaft. This shaft carries a selector 6 consisting of a single element of segmental form, and toothed longitudinally or parallel with the axis of rotation of the shaft 3. The selector member is mounted on the shaft by the arms 7. To one side of the selector member a group of transmitting elements 8 in the form of segments or wheels normally lie, as shown in Figs. 1 and 2, these elements being mounted to turn freely about a shaft or rod 9 suitably supported in the framework. These transmitting elements are suitably spaced apart by interposed collars 10, and they lie between the upstanding arms 11 of a carriage which comprises a rack bar 12 controlled in its movement by pawls 13 and 14 pivotally mounted on a shaft 15, which, in turn, is mounted in the side frames of the machine. The arms 11 are provided with forked lower ends 16, which engage a rod 17 fixed in the frame, by which the transmitting gear carriage is guided and held in position. The transmitting wheels or segments are toothed to correspond with the teeth of the selector member for engagement therewith. The carriage is impelled toward the left by a lever 18 connected pivotally thereto at 19, and suitably pivoted to the frame at 19, a spring 20 being connected with the lever to force it toward the left of Fig. 1, when the escapement pawls are operated. The shaft carrying the escapement pawls is operated from a space frame 21 consisting of the cross bar and the pivoted supporting arms 22. A lever 23 extends from the axis 24 of the supporting arms, and is connected through a link 25 and an arm 26 with the escapement shaft 14, so that each time a key is depressed, the first action will be to turn the shaft 3 to set the toothed selector segment 6 in proper angular position according to the value of the key struck, and the second action will be to turn the escapement pawls to impel the transmitting gear carriage toward the left. The escapement pawls are controlled by a lever 27 connected to the lever 23, and the lever 27 is controlled by a lever 28 connected to the lever 18, so that the escapement pawls will be turned each time a key is depressed.

to the value of the key, and then the continued downward movement of the key will operate the space frame 21 and this, through the lever 23 and the connections described, 5 will turn the escapement shaft 14 to throw one pawl out of engagement with the escapement rack and the other pawl into line therewith, so that the left feed of the transmitting gear carriage will be effected. The 10 feed toward the left is step by step, one step being accomplished for each depression of one of the keys, and at each action one of the transmitting segments will be thrown into engagement with the teeth of the selector, and if a number of keys are operated 15 in succession, the transmitting wheels or segments will be turned in succession or one after the other, and thus by the leftward movement of the carriage, they will be engaged with the selector in different angular positions, according to the values of the keys operated, it being understood that for each operation of the key the selector is turned to different angular positions, so that upon the 20 release of the key the transmitting elements will be set back in the different relative positions to each other, according to the different positions assumed by the selector when the several transmitting wheels or 25 segments engage therewith. The desired number of transmitting wheels or segments having been engaged with the selector, the next action is to transfer these values onto the totalizer wheels. These wheels are indicated at 27, and are normally disengaged from the transmitting gears or wheels, and for accomplishing this transferring action, a hand lever 28 is employed connected with a shaft 29 geared through the toothed wheel 30 and the wheel 31, with a shaft 32 suitably mounted in the frame, the connection being made through an interposed spring clutch 33, by which, when the handle is turned one way, motion will be communicated to the 35 shaft 32, whereas when the handle is reversed, no movement will be communicated because the clutch on this movement will slip. The shaft 32 is connected through gears 33', 34, with a cam shaft 35 upon 40 which is mounted a cam 36. The rotation of this cam, when the handle is drawn forward, will operate upon a roller 37 carried by a lever 38 pivotally mounted at 39 in the frame, the forward end of said lever being 45 connected through a link 40 with an arm 41 fixed to the shaft 3, so that it will be seen the operation of the hand lever will, through the connections described, move the selector segment in the direction of the arrow, 50 Fig. 3, and thus turn all of the transmitting gears which may be in engagement therewith upwardly on the left Figs. 3 and 4 to make these gears engage the gears of the totalizer wheels 27, resulting in transferring 55 the values onto these totalizer wheels. The position of the selector member 6 with relation to the transmitting wheels 6' in their normal position is that which is necessary for adding the number 9. When one of the numeral keys is depressed, the shaft 3 and 60 the selector 6 mounted thereon will be turned through a distance corresponding to the difference between 9 and the figure struck; that is, depression of the 9 key will not rotate the shaft 3 and the selector 6 at all, but will simply operate the escapement. Depressing the 8 key will raise the selector 6 one tooth, and so on.

After the values have been transferred to the totalizer wheels by the operation of the transmitting gears, the further rotation of the cam shaft 35 will cause a cam 42 to act on a roller 43 of the lever arm 44, and this, through a link 45 and bell crank lever 46, will move the pawl 13 to force the transmitting wheel carriage toward the right one step to disengage the transmitting wheels from the totalizer wheels and make them occupy positions in line with the spaces between said totalizer wheels. These transmitting gears, however, will still remain in engagement with the selector. The further rotation of the cam shaft 35 will now bring the cam 36 into engagement with the roller 47 on the lever 38, and give a reverse movement to said lever from that which the cam 36 previously gave it, with the result that through the link 40 and arm 41 the selector segment will be returned to normal position, and the transmitting gears to their set back 70 position, namely, their respective angular positions which they assumed as a result of the first operation of the figure keys, the turning of the selector, and the lateral movement of the transmitting gear carriage. The further forward movement of the handle now acts through a cam 48 on the shaft 35, and a roller 48 on the lever or arm 49 to return the carriage lever 17 toward the right by means of the link 50, resulting in the return of the whole group of transmitting gears to their disengaged position at the right of the plane of the selector, as shown in Fig. 1. This action withdraws the transmitting gears from beneath the totalizer, so 80 that they will then occupy their original position at the right of these totalizers and the selector. The position of the transmitting gears which have been displaced into angular position and are engaged with the selector 6 when that selector is in its normal position is such that they will pass under the rigid arm 51 when the transmitting gear carriage is moved to the right from under the totalizer. At the completion of this 85 withdrawing action toward the right, a cam 52 on the cam shaft 35 acting on the roller 53 of the lever 54 will operate the said lever, which, through a link 55, and an arm 56 on the shaft 8, will rotate the said shaft, and 90

as this shaft carries an alining bar 57, this, contacting with the displaced transmitting gears, will turn them about the shaft 8 until they are all forced up against the bar 51, 5 and thus into accurate alignment in their normal angular position.

Subtracting: When it is desired to subtract instead of add, the operations above described are practically the same, excepting that the subtracting key 58 is pressed inwardly while the handle 28 is pulled forward. This subtracting key 58 operates through a bell crank lever 59 pivoted at 60 to move the cam 42 along the cam shaft 35 against the tension of the spring 61 out of position to engage the roller 48 of the lever 44, which is employed for shifting the carriage one step toward the right, and this action brings a cam 42^a into position to engage this roller, so that as the transmitting gears are rotated upward as a result of the forward movement of the handle 28 and the turning of the cam 36, the group of transmitting gears will have been moved by means of the cam 42^a, the lever 44, the link 45 and bell crank 46 and pawl 13, one step toward the right, this action taking place previous to the action of the cam 36 on its connection, so that as the transmitting gears are turned up, they will not engage the totalizing wheels, but will move in the spaces between these totalizing wheels to positions ready to engage the same by a lateral movement of the transmitting gear carriage, and this lateral movement for engaging the transmitting gears with the totalizer wheels will take place as a result of the release of the connections just described from the cam 42^a, and the coming into play of the spring 20 and shifting lever 17. After the transmitting gears have been moved as described in between the totalizer wheels, and have engaged the same by a lateral movement, the cam 36 acting through the connections mentioned, will return the selector 6 to normal position and the transmitting gears to their set back position, with the result that the values will be subtracted from the totalizer wheels.

Multiplying: For multiplying or repeating a number, a multiplying key 62 is employed, this being pressed in while the handle 28 is drawn forward. This key, acting through the bell crank lever 63, will withdraw the roller 64 from the path of the cam 48^a so that as the shaft 35 rotates, the cam 48^a will exert no pressure against the roller 48 because it is not backed by the roller 64. The action of this cam upon the roller 48 depends upon whether or not its inclined edge engages the roller 64 to press the cam longitudinally of the shaft 35, it being observed from Fig. 1 that the hub of the cam is splined by a pin and slot connection at 65 to the shaft 35. As the

cam turns with the roller 64 in normal position, its inclined edge riding against the roller will force the cam along the shaft, and thus acting upon the roller 48, the arm 49 will be operated to return the carriage 70 to the right, but if the roller 64 is displaced, as above described, by pressing in the multiplying lever 62, when the lever 28 is drawn forward, there will be no action of the cam upon the roller 48, and thus the transmitting gear carriage will remain in position, and repeated operations of the handle or lever 28 will throw the same selection of transmitting gears into mesh with the totalizer at each motion of the handle, thus securing repeated action for multiplying until the key 62 is released, when the roller 64 will be returned to normal position to act on the cam, and cause the withdrawing of the transmitting gear carriage to the right 85 when the handle is next operated. The cams 42 and 42^a are mounted on a sleeve which has a circumferential groove 66 engaged by a pin 67 of the lever 59, whereby the cams may be shifted longitudinally of 90 the shaft 35, and the said cams are held to rotate with the shaft by a pin 67' entering a slot 68. To briefly describe the operation, when a key is depressed, the selector 6 will be turned into an angular position to the 95 shaft 3 corresponding to the value of this key, and having come to rest, the transmitting gear carriage is shifted to bring the first transmitting gear or that which lies at the left of the group in Fig. 1 into engagement with its teeth with those of the selector. The selector then returns to normal position, and consequently the first transmitting gear will be set back into an angular position in relation to the rest of the 100 group of transmitting gears corresponding to the value of the key struck. It may be here stated that the leftward movement of the group of transmitting gears frees them from control of the positioning bar 51 and 105 the return bar 57, so that they are free to turn about the shaft 8. When another key is depressed, and supposing this to be of different value from that first depressed, the selector 6 will be turned into an angular position different from that resulting 110 from the operation of the first key, and having come to rest, the transmitting gear carriage will be given another step movement leftward, shifting the first transmitting gear farther along the selector, but maintaining engagement with the long teeth on the face thereof, and the second transmitting gear or segment will be thrown into engagement with the selector, and when 115 this returns to normal position, this second transmitting gear will be turned to an angular position corresponding to the value of the key struck, and supposing, as above stated, that this key is different in value 120

125 130 135

from that first operated, the angular position of this second transmitting gear will be different from that of the first, and as other keys of different values are struck, the selector will be turned into different angular positions to be engaged by the remaining transmitting gears in succession, so that when the operation is completed, we will have the selector back in normal position but engaged by a plurality of transmitting gears occupying different angular positions in respect to the shaft 8, according to the values of the operated keys. Upon the operation of the handle, the selector will be moved in the direction of the arrow, Fig. 3, and the differently set transmitting gears will engage the totalizer wheels and transfer thereto the different values, according to the angular positions of the transmitting gears. The transmitting gear carriage, at the completion of this transferring action, will now be shifted one space to the right by the cam 42, and the cam 36 then acting, will return the selector to normal position and the transmitting gears to their set back angular positions, and following this action, the cam 48^a will return the whole group of transmitting gears to the right to the position shown in Fig. 1, and following this the differently set transmitting gears will be borne upon by the returning arm 57, and they will be turned about the axis 8 from their different angular positions to be lined up by contacting 35 with the under side of the bar 51.

In order to eliminate errors, I provide a key at 66 which is connected with the bell crank lever 46. By the operation of this key the carriage of the transmitting gears may be shifted to withdraw the said gears out of connection with the totalizer wheels, and to set them opposite the spaces between the said totalizer wheels, so that, upon the operation of the hand lever, no transferring 45 action will take place.

The totalizer may be of any approved type. I prefer to arrange the transmitting wheels in a position to add the number 9 when in normal relation to the other parts, 50 because in this way I can employ such a connection between the keys and the shaft of the selector that the movement of the shaft under the action of the keys will be in the same direction with that imparted to the 55 shaft when the hand lever is operated. In other words, when a key is operated, the pin on its hub will strike the pin on the shaft, and turn the same toward the left at its upper part, and when the hand lever is operated, the shaft will turn in the same direction, its pin moving away from the pin on the hub of the key lever, and thus having no conflict therewith. Repeated subtrac- 60 tions may be effected by pressing in the sub-

tracting key and the multiplying key, and 65 operating the handle.

I claim as my invention:—

1. In combination in a machine of the class described, a toothed selector, a group of transmitting elements, and means including keys for first adjusting the selector to its different positions according to the values of the keys struck, and for connecting the adjusted selector with the transmitting elements *seriatim*, and totalizer means to receive the values from the transmitting elements, substantially as described. 75

2. In a machine of the class described, a selector, a totalizer, a group of transmitting elements movable to different positions individually, means for moving the selector to different positions according to the values of the keys operated and for throwing the selector and the transmitting elements into engagement so that a number of said elements may engage the selector simultaneously, and means for operating the selector for moving all the engaged transmitting elements for transferring the selected values onto the totalizer, substantially as described. 85

3. In a machine of the class described, a selector, a totalizer, a group of transmitting elements movable to different positions individually, means for moving the selector to different positions according to the values 95 of the keys operated, and for shifting the group of transmitting elements to make the desired number engage with the selector, and means for operating the selector for moving all the displaced transmitting elements for transferring the selected values onto the totalizer, substantially as described. 100

4. In a machine of the class described, a selector member, a totalizer, a group of transmitting elements turnable individually 105 to different angular positions, means for turning the selector to different angular positions according to the values of the keys operated, and for shifting the group of transmitting elements to throw the desired 110 number of transmitting elements into engagement with the selector, and means for operating the selector for moving all the displaced transmitting elements for transferring the selected values onto the totalizer, 115 substantially as described.

5. In a machine of the class described, a selector member, a totalizer, a group of transmitting elements turnable individually 120 to different angular positions, means for turning the selector to different angular positions according to the values of the keys operated, and for shifting the group of transmitting elements to throw the desired 125 number of transmitting elements into engagement with the selector, and means for operating the selector for moving all the displaced transmitting elements for transfer-

ring the selected values onto the totalizer, the said transmitting elements being normally out of connection with the totalizer and being thrown into engagement therewith by the movement of the selector, substantially as described.

6. In apparatus of the class described, a toothed selector member, key connections for first turning the same from its normal to different angular positions according to the values of the keys struck, a group of toothed transmitting members, a carriage therefor, and key controlled means for moving the carriage after the selector has been turned from its normal position, to make the transmitting elements engage the selector in its displaced positions, substantially as described.

7. In combination in a machine of the class described, a toothed selector, a group of transmitting elements individually adjustable, key connections for turning the selector and throwing the transmitting elements and the selector into engagement until the desired number are in connection, said selector returning to normal position after each engagement by a transmitting element, a totalizer, and means for operating the selector and transmitting elements to cause the engagement of said elements with the totalizer, substantially as described.

8. In combination in a machine of the class described, a toothed selector, a group of transmitting elements individually adjustable, key connections for turning the selector and throwing the transmitting elements and the selector into engagement until the desired number of elements are in connection with the selector, said selector returning to normal position after each engagement therewith by a transmitting element, a totalizer, and means for operating the selector and transmitting elements to cause the engagement of said elements with the totalizer, said means including a handle, and connections operated thereby after the keys have been operated, substantially as described.

9. In combination in a machine of the class described, a single selector pivotally mounted and having a curved face concentric with its axis, and having teeth extending parallel with the axis from end to end, a group of transmitting elements toothed to engage the teeth of the said selector, key controlled connections for turning the selector into different angular positions, and for causing engagement of the selector and the transmitting wheels in succession upon successive operations of the selector from the keys, a totalizer, and means for operating the selector and transmitting elements to transfer the key values onto said totalizer, substantially as described.

10. In combination in a machine of the

class described, a single selector pivotally mounted and having a curved face concentric with its axis, and having teeth extending parallel with the axis from end to end, a group of transmitting elements toothed to engage the teeth of the said selector, key controlled connections for turning the selector into different angular positions, an escapement and carriage with key connections thereto, operating after the selector has been turned, to connect the selector and the transmitting elements in succession upon successive operations of the keys, a totalizer, a handle, and connections operated by the handle for controlling the selector and the transmitting wheels in engagement therewith for transferring the values of the operated keys onto the totalizer, substantially as described.

11. In combination in a machine of the class described, a totalizer, a group of transmitting elements, means for selecting said transmitting elements and setting them in different displaced positions relative to each other according to the values of the keys operated, means for then advancing the displaced selectors in respect to the totalizer, and means for then shifting the transmitting elements axially to disengage from the totalizer and returning them to their former positions, substantially as described.

12. In combination in a machine of the class described, a selector, a group of transmitting elements normally arranged in disengaged position at one side thereof, a totalizer, key connections for turning the selector and then shifting the group of transmitting wheels to engage in order with the selector as the keys are struck in succession, means for turning the selector to turn the transmitting elements, means for then shifting the transmitting elements axially, after which the selector returns to normal position to turn the transmitting elements back, and means for then shifting the group of transmitting elements out of engagement with the selector, substantially as described.

13. In combination in a machine of the class described, a selector, a group of transmitting elements normally arranged in disengaged position at one side thereof, a totalizer, key connections for turning the selector and then shifting the group of transmitting wheels to engage in order with the selector as the keys are struck in succession, means for turning the selector to turn the transmitting elements into engagement with the totalizer for transferring the values onto the same, means for then shifting the transmitting elements axially into position opposite the spaces between the totalizer wheels, after which the selector returns to normal position to turn the transmitting elements back, and means for then

shifting the group of transmitting elements out of engagement with the selector, substantially as described.

14. In combination in a machine of the class described, a totalizer, a group of transmitting elements to engage and turn the same, selector means for setting the transmitting elements in different angular positions, means for advancing the transmitting elements to engage and turn the totalizer, means for then shifting the transmitting elements axially to disengage the totalizer, and for returning the transmitting elements to their set back positions, substantially as described.

15. In combination in a machine of the class described, a totalizer, a group of transmitting elements, means for setting said elements in different angular positions as the keys are struck, means for advancing the transmitting elements in the spaces between the totalizer wheels and for then shifting the transmitting elements axially to engage the totalizer wheels, and means for returning the transmitting elements while engaging the totalizer for subtracting, substantially as described.

16. In combination in apparatus of the class described, a selector, totalizer wheels, a group of transmitting elements normally disengaged to one side of the selector, key connections for operating the selector and shifting the transmitting elements into engagement therewith as the keys are struck in succession, a hand operated device for advancing the transmitting elements, means for then shifting the transmitting elements into connection with the totalizer wheels for subtracting, for then returning the transmitting elements to their former positions, and for shifting the group of transmitting elements axially to disengaged position to one side of the selector, substantially as described.

17. In apparatus of the class described, a selector, a group of disengaged transmitting elements normally disengaged at one side thereof, a totalizer, key connections for operating the selector to different angular positions according to the values of the keys operated, and for then shifting the group of transmitting elements axially to engage the selector in succession as the keys are struck, a cam shaft, a handle for operating the said shaft, connections between the cam shaft and the selector for giving a forward and backward movement to the selector, connections from the cam shaft for shifting the group of transmitting wheels one step axially, and connections between the cam shaft and the group of transmitting elements for shifting them axially to disengaged position at one side of the selector, substantially as described.

18. In combination in a machine of the

class described, a totalizer, a selector, a group of transmitting elements, a shaft carrying the selector, keys loosely connected with said shaft to turn the same to different degrees respectively, connections operated by the keys for throwing the selector and the successive transmitting elements into engagement as the keys are struck in succession, a hand operated device, and a connection between the same and the selector shaft for turning the same, substantially as described.

19. In combination in a machine of the class described, a selector mounted to turn, a group of transmitting elements, key connections for turning the selector and for shifting the transmitting elements and the selector into engagement, a totalizer, a hand operated device, a cam operated thereby, and a connection between the cam and the selector for first moving it forward and then backward, substantially as described.

20. In combination in a machine of the class described, a selector, a group of transmitting elements, key connections for turning the selector to different angular positions, and shifting the transmitting elements into engagement with the selector as the keys are struck in succession, a totalizer, a hand operated device with connections to the selector to turn the same to advance the transmitting elements, connections operated by the continued movement of the hand operated device in one direction for shifting the group of transmitting elements axially one step, and connections operated by the further movement of the hand operated device in the one direction for withdrawing the group of transmitting elements to disengaged positions after being turned back, substantially as described.

21. In combination in a machine of the class described, a selector, a totalizer, a group of transmitting elements normally disengaged from the selector, key connections for turning the selector into different angular positions and for engaging the transmitting elements successively with the selector as the keys are struck in succession, a totalizer, a hand operated device, and connections operated thereby for advancing the selector and transmitting elements, shifting the said elements axially, returning the selector and said elements, and then shifting the group of elements to their disengaged position, substantially as described.

22. In combination in a machine of the class described, a selector, a totalizer, a group of transmitting elements normally disengaged from the selector, key connections for turning the selector into different angular positions and for engaging the transmitting elements successively with the selector as the keys are struck in succession, a totalizer, a hand operated device, and con-

nections operated thereby for advancing the selector and transmitting elements, shifting the said elements axially, returning the selector and said elements, and then shifting the group of elements to their disengaged position, said connections including a cam shaft operated by the handle, cams thereon, and connections from said cams to the selector and transmitting elements, substantially as described.

23. In combination in a machine of the class described, a totalizer, a selector, a group of transmitting gears, key connections for turning the selector and shifting the transmitting elements into engagement therewith in succession as the keys are successively operated, means for transferring the values from the transmitting gears to the totalizer and for returning the group of transmitting gears to disengaged position in respect to the selector after transferring the values onto the totalizer, and means for turning the angularly displaced transmitting gears back to normal position, substantially as described.

24. In combination in a machine of the class described, a totalizer, a selector, a group of transmitting gears, key connections for turning the selector and shifting the transmitting elements into engagement therewith in succession as the keys are successively operated, means for transferring the values from the transmitting gears onto the totalizer and for returning the group of transmitting gears to disengaged position in respect to the selector after transferring the values onto the totalizer, and means for turning the angularly displaced transmitting gears back to normal position, said means including a bar extending parallel with the shaft of the transmitting gears, and hand operated connections for giving said bar a revolving movement about the said shaft, and an alining or stop bar against which the transmitting gears strike, substantially as described.

25. In combination in a machine of the class described, a single toothed selector, a group of transmitting gears arranged to lie at one side of the selector but in disengaged position, a totalizer, key connections for operating the selector to different angular positions, and for shifting the group of transmitting gears into engagement with the selector in succession as the keys are struck, a hand operated device with connections for turning the selector to throw the transmitting gears into engagement with the totalizer, and for returning the selector with the transmitting gears, connections for then shifting the group of transmitting gears to disengaged position, a stop bar extending parallel with the shaft of the transmitting gears, a rotary return bar to engage the transmitting gears for

returning them from their angularly displaced positions to their normal position, and connections for operating the return bar, substantially as described.

26. In combination in a machine of the class described, a single selector, a group of transmitting gears normally disengaged therefrom and lying at one side thereof, a totalizer, key connections for turning the selector and for engaging the transmitting gears in succession therewith, a hand operated device with connections for turning the selector to move the transmitting gears to the totalizer, a carriage for the transmitting gears, a cam operated by the hand operated device with connections for shifting the carriage one step, and a cam with connections for shifting the transmitting gear carriage to disengaged position, substantially as described.

27. In combination in a machine of the class described, a selector, a group of transmitting gears normally disengaged therefrom and lying to one side thereof, a totalizer, key connections for turning the selector and then shifting the transmitting gears into mesh therewith in succession as the keys are struck, a hand operated device with connections for turning the selector to throw the transmitting gears to and from the totalizer for performing addition, and a controlling member or key for performing subtraction by the operation of the said selector and transmitting gears by the said hand operated device, substantially as described.

28. In combination a single selector, key connections for turning the selector to different angular positions, a group of transmitting gears shiftable axially to engage the displaced selector, a totalizer, means for operating the said parts to perform addition by moving the selector in one direction to cause the transmitting gears to turn the totalizer and then to return the said transmitting gears while in line with the spaces between the totalizer wheels, and means for adjusting the said transmitting gears for performing subtraction by setting the said transmitting gears first in line with the spaces between the totalizer wheels for their forward movement, the said transmitting gears being in engagement with the totalizer wheels during their return movement, substantially as described.

29. In combination in a machine of the class described, a selector, a group of transmitting gears normally disengaged therefrom at one side thereof, key levers for turning the selector and shifting the transmitting gears in succession into engagement with the selector, a totalizer, hand operated means for turning the selector for throwing the transmitting gears into engagement with the totalizer for effecting addition, means for shifting the group of transmitting gears

- one step axially to free them from the totalizer for their return to their normal position, means for then shifting the group of transmitting gears to disengaged position, 5 and a subtracting key with means controlled thereby for shifting the group of transmitting gears into line with the spaces between the totalizer gears previous to advancing the transmitting gears, whereby, upon the 10 return of the transmitting gears, subtracting will be performed, substantially as described.
30. In combination a selector, a group of transmitting gears normally disengaged at one side thereof, a totalizer, key connections 15 for throwing the selector into different angular positions, and for shifting the transmitting gears in succession into engagement with the selector as the keys are operated in succession, a hand operated device for turning the selector, together with the transmitting gears, to transfer the values onto the totalizer, means for shifting the group of transmitting gears to disengaged position, and a multiplying key with connections for 20 throwing the said shifting mechanism out of service whereby, upon repeated operations of the hand operated device, multiplying will be effected, substantially as described.
31. In combination in a machine of the class described, a selector, a group of transmitting gears normally disengaged at the right thereof, means for turning the selector and for shifting the transmitting gears into 25 engagement therewith, a totalizer, a hand operated connection for turning the selector to throw the transmitting gears into connection with the totalizer, a cam with connections operated by the hand operated device for re- 30 turning the transmitting gears to disengaged position, said cam being movable axially to effect the said shifting movement, a bearing against which the cam works, and a multi- 35 pling key connected to the said bearing for shifting it to and from operative position whereby the said shifting mechanism may be thrown out of service for multiplying by 40 repeated operations of the hand operated device, substantially as described.
32. In combination in a machine of the class described, a selector, a shaft carrying the same, a group of transmitting gears normally disengaged from the selector and lying to one side thereof, key connections 45 for turning the selector to different angular positions and for shifting the transmitting gears in succession into engagement therewith, a hand operated device with connections for turning the selector and the transmitting gears to make the latter turn the totalizer, a cam with connections for shifting the transmitting gears one step into line with the spaces between the totalizer gears for the 50 return movement of the transmitting gears by the continued operation of the hand op- 55 erated device, a second cam, with a subtracting key for throwing the first cam out of service and the second cam into service for shifting the group of transmitting gears into line with the spaces between the totalizer gears, said cam being positioned to perform its function prior to the advance movement of the transmitting gears to the totalizer, and allowing the transmitting gears to shift one step for engagement with the totalizer after the advance movement has been performed, whereby, upon the return of the transmitting gears, subtracting will be performed, substantially as described.
33. In combination in a machine of the class described, a single selector, a shaft upon which the same is mounted, said selector being toothed parallel with the said shaft, a group of transmitting gears normally disengaged from the selector and lying to one side thereof, key connections mounted upon the selector shaft loosely with means of connection whereby the different keys will turn the shaft to different degrees, an escapement carriage for the group of transmitting gears, connections to the keys for operating the escapement for shifting the transmitting gears in succession into engagement with the selector, a hand lever, a cam shaft operated thereby, a cam having 95 connections therewith to the selector shaft for turning it forwardly and backwardly for turning the selector to throw the transmitting gears to and from the totalizer, a cam on the said shaft with connections for shifting the transmitting gear carriage one step opposite the spaces between the totalizer wheels for the return of the transmitting gears to their different angular positions, and a cam on the shaft with connections for 100 returning the transmitting gear carriage to disengaged position, substantially as described.
34. In combination in a machine of the class described, a selector, a group of transmitting gears, key connections for setting the selector in different angular positions and for then shifting the group of transmitting gears to make them engage with the selector in succession, a hand operated device for operating the selector to throw the transmitting gears to the totalizer, and a correcting key with connections to the transmitting gears for shifting them one step for 105 their return without affecting the totalizer, substantially as described.
35. In combination a totalizer, a group of transmitting gears, means for setting the gears in different angular positions according to the values of the operated keys, and for shifting the transmitting gears into positions opposite the gears of the totalizer but not into connection therewith, and means for then turning the transmitting gears to engage the totalizer and transfer 110
- 115
- 120
- 125
- 130

the values upon the same, substantially as described.

36. In combination a totalizer, a group of transmitting gears, normally in position to add the figure 9, a selector, key connections for turning the selector to different angular positions for adding digits less than 9 and for shifting the group of transmitting gears into connection therewith whereby said transmitting gears will be turned back to position for adding the said digits less than 9, and means for turning the transmitting gear to transfer their values onto the totalizer, substantially as described.
37. In combination a totalizer, a group of transmitting gears, a selector, key connections for turning the selector and for shifting the transmitting gears into connection therewith, and a handle with means for turning the selector in the same direction as the keys for throwing the transmitting gears to the totalizer, substantially as described.
38. In combination a totalizer, a group of transmitting gears, a selector, a shaft, keys having connection with the shaft for turning the same in one direction, said shaft being turnable independent of the keys, and a handle with connections for turning the shaft in the same direction as the keys to turn the transmitting gears to the totalizer, substantially as described.
39. In combination in a machine of the class described, a totalizer, a group of transmitting gears, a selector, key connections for operating the selector, and for connecting the selector and transmitting gears, and means for turning the selected transmitting gears to transfer the values onto the totalizer, and means for returning the transmitting gears to disengaged position, and means for eliminating the function of said returning mechanism whereby repeated transfer of values may be effected, substantially as described.
40. In combination in a machine of the class described, a selector, a group of transmitting gears to connect therewith as the keys are struck in succession, a totalizer, means for turning the selector to turn the transmitting gears in relation to the totalizer, means for shifting the transmitting

gears axially to engage with or disengage with the totalizer, and controlling means to determine whether said engagement be for addition or subtraction, substantially as described.

41. In combination in a machine of the class described, a single selector, a group of transmitting gears, key operated connections for connecting the selector and the transmitting gears, and means for turning the transmitting gears forward and backward, and for shifting them axially while still maintaining their engagement with the selector, substantially as described. 65

42. In combination in a machine of the class described, a totalizer, a group of transmitting gears to operate the totalizer, means for selecting the transmitting gears, means for turning the transmitting gears to turn the totalizer, means for shifting the transmitting gears one step axially to disengage from or engage the totalizer, means for shifting the group of transmitting gears axially to disengaged position, and means for eliminating the function of the shifting means last mentioned to repeat the movement of the transmitting gears onto the totalizer, substantially as described. 70

43. In combination a totalizer, a group of transmitting gears, selector means for the transmitting gears, means for turning the transmitting gears forward and backward, means for shifting the transmitting gears, a controlling device to determine whether said shifting movement will take place before or after the transferring action of the transmitting gears upon the totalizer whereby subtraction may be performed, means for shifting the transmitting gears to their disengaged positions, and means for eliminating the functions of said shifting means whereby repeated actions of the transmitting gears upon the totalizer may be effected, substantially as described. 85 90 95

In testimony whereof, I affix my signature in presence of two witnesses.

SYDNEY B. AUSTIN.
